UNITED STATES PATENT OFFICE.

EDWARD S. STIMPSON, OF HOPEDALE, MASSACHUSETTS, ASSIGNOR TO DRAPER CORPORATION, OF HOPEDALE, MASSACHUSETTS, A CORPORATION OF MAINE.

WARP STOP MOTION FOR LOOMS.

1,418,494.

Specification of Letters Patent. Patented June 6, 1922.

Application filed August 22, 1921. Serial No. 494,297.

To all whom it may concern:

Be it known that I, EDWARD S. STIMPSON, a citizen of the United States, residing at Hopedale, in the county of Worcester and

5 State of Massachusetts, have invented an Improvement in Warp Stop Motions for Looms, of which the following description, in connection with the accompanying drawings, is a specification, like characters on the 10 drawings representing like parts.

This invention relates to warp stop motions for looms, and more particularly to the drop wires employed in such mechanisms.

15 In that type of warp stop motion wherein the drop wires are supported by the warp thread during weaving and are dropped or released when a warp thread becomes broken or too slack for weaving purposes, it is the 20 common practice to string the drop wires upon drop wire guides or bars which not only serve to guide the drop wires in their vertical movements, but also to receive the pressure of the feeler when it is stopped by 25 a dropped wire.

Should the pressure of the feeler against the drop wire twist or deflect the latter relatively to the drop wire guide, the feeler will fail to be arrested, and the loom will continue to run and weave imperfect cloth. The 30 slot or opening in the drop wire is died out or stamped, and must be made with considerable accuracy because, should it be formed to fit too snugly, the drop wire will 35 not drop to its proper stopping position, in which case the loom would fail to be stopped, and imperfect cloth would be woven. On the other hand, if the amount of clearance between the guide and the walls of the drop 40 wire slot is made sufficiently large to insure proper dropped position of the drop wire when released by a warp thread, the drop wire is liable to be twisted or turned about a vertical axis under the pressure of the 45 feeler, in which case the loom will again continue to run and produce imperfect cloth.

The die by which the slot in the drop wire is formed is sharpened or ground from time to time, with the result that should the slot 50 in any set of drop wires first made by the die fit the drop wire guide with sufficient accuracy to prevent either of the above-named objections, the drop wires which are later produced by the same die after it has been

ground or sharpened, would be too loose, 55 and on pressure of the feeler, it would twist or turn on the drop wire guide and fail to stop the loom.

It is important, therefore, that the drop wires be so formed that regardless of any 60 variation in the side of the drop wire slot due either to wear or by grinding of the die which cuts the slots, the pressure wall of the slot (that is, the wall which transmits the pressure of the feeler to the feeler guide) 65 shall bear firmly upon the adjacent wall of the drop wire guide when the drop wire is in its dropped position.

An important feature of the present invention, therefore, consists of a drop wire 70 having a drop wire guide slot or opening, the bearing wall of which is vertical and the opposite or positioning wall of which is inclined to the vertical and converges upwardly relative to the bearing wall, the construction being such that the positioning wall insures a firm contact of the opposite bearing wall with the adjacent surface of the guide, regardless of variations in the 75 width of the drop wire slot or opening.

The invention will best be understood from the following description and accompanying drawings of one good, practical form thereof, wherein:

Figure 1 is a sectional view of a portion 80 of a warp stop motion, showing the drop wires in their lowered or stopping position;

Fig. 2 is a partial plan view of Fig. 1, showing more particularly one of the drop wires in its dropped position and the feeler 90 being arrested in its feeling movement.

The warp stop mechanism may comprise the side supports 1 carrying the warp supporting rods 2 over which pass the warp threads 3. The side supports 1 furnish a 95 convenient means for supporting the feeler slide 4 on which are mounted the feelers 5. In the present instance of the invention the feelers 5 are indicated as inclined to the vertical, and as having the vertical walls 6 for 100 engagement with the drop wires as will later be explained; but so far as the present invention is concerned, the feelers may be of any of the well known and usual types, wherein they are given a detecting or reciprocating 105 movement toward and from the drop wires. In this respect the side supports 1, the feeler carrier slides 4, and the feelers 5, may be sub-

stantially as more fully described in the application of Edward S. Stimpson, Serial Number 474,368, filed June 2, 1921.

Extending between the side supports 1 of 5 the warp stop mechanism are the drop wire guides 7, which pass through slots 8 extending longitudinally of the drop wires. In the form of drop wire shown, each is provided with an opening 9 through which one of the 10 warp threads 3 passes, but so far as the present invention is concerned, this feature of the drop wire may be of any usual or well known construction, the sole requirement being that the drop wires may be normally held in their 15 raised position by normal warp threads.

Each of the drop wires is provided with an enlarged head 10 which, when a drop wire is dropped by a broken or too slack warp thread, is engaged by the associated feeler 5 20 to effect loom stoppage.

The construction of the drop wires and drop wire guides as thus far described may be the same as well known in the prior art and as illustrated in Fig. 3. In the old form 25 of drop wires, the upper portion of the slot or opening in a drop wire has usually been formed with the side walls substantially parallel to the adjacent surfaces of the drop wire guide with a comparatively large amount of 30 clearance between the walls and the sides of the drop wire guide and when the feeler has engaged the upper portion of the drop wire upon the breakage of a warp thread, the drop wire has been unable to support the pressure 35 of the feeler without twisting movement, the result being that the feeler has not been arrested and the loom has continued to run. The twisted or turned condition of the drop wire is well indicated in Figs. 4 and 5.

40 In the present invention, that portion of the opening in the drop wire which is engaged by the drop wire guide when the drop wire has been released by a broken or unduly slack warp thread, is formed with a bearing wall 15 which bears against the surface 16 of the drop wire guide when the drop wire is in 45 its lowered position as indicated in Fig. 1. In order to insure the firm bearing of the bearing wall 15 against the surface of the 50 drop wire guide whenever the drop wire is released by a broken or unduly slack warp thread, the wall 17 of the slot or opening opposite the vertical bearing wall is formed inclined and constitutes a positioning wall 55 which engages the upper portion of the adjacent surface 18 of the drop wire guide when the drop wire is in its lowered position. The construction is such that the vertical bearing wall 15 is always brought into close contact- 60 ing relation with the adjacent surface 16 of the drop wire guide by the action of the inclined positioning wall 17 when a drop wire is released by a warp thread, and consequently all clearance between the bearing wall 15 and the adjacent surfaces 16 of the

drop wire guide is taken up, regardless of any variation in size of the slot between the bearing and positioning walls 15 and 17, respectively. When pressure is exerted by the feeler 5 against a lowered drop wire, as indicated in Fig. 1, and the bearing wall 15 is held firmly against the adjacent surface of the drop wire guide by the opposite inclined positioning surface 17, the drop wire is firmly held and prevented from being twisted or 75 deflected by the feeler, and the loom is unerringly stopped.

As hereinbefore mentioned, the drop wires are died out and it becomes necessary from time to time to grind or sharpen the die. 80 The result is that the width of the opening in the drop wires between the bearing and positioning walls 15 and 17, will vary. This opening in the drop wires which are died out after the die has been ground or 85 sharpened, will be somewhat wider than the opening in the drop wires which are died out prior thereto; and where the opening in the drop wires is of the old form, as indicated in Fig. 3, the later-died-out drop wires have 90 so much clearance between the walls of the opening and the drop wire guide that they become deflected and twisted under the action of the feeler. In accordance with the present invention, however, the bearing wall 95 and the positioning wall of the slot in the detector are so related as hereinbefore described, that even though the distance between said walls 15 and 17 may vary, the bearing wall 15 will always be forced into 100 intimate bearing and flush contact with the adjacent wall 16 of the drop wire guide, so that the drop wire is always held firmly in position to resist the pressure exerted by the feeler, without twisting.

105 The effect of the different widths in the upper portion of the openings in drop wires made by the die before and after sharpening, is indicated in Fig. 1, wherein the drop wire at the left is typical of those died out prior to the sharpening of the die, whereas those at the right typify drop wires died out after the die has been ground or sharpened. In either case, however, the bearing surface 15 is caused to contact firmly with and be 110 clamped upon the adjacent surface 16 of the guide and consequently prevent deflection or 115 twisting of the drop wire under the pressure of the feeler.

120 What is claimed is:—

1. In a warp stop motion for looms, the combination of a drop wire having an opening provided with a bearing wall extending parallel to the longitudinal axis of the drop wire and an opposite positioning wall inclined to the longitudinal axis of the drop wire and converging upwardly toward the bearing wall, a drop wire guide extending through the opening of the drop wires and having a face adapted to engage the bearing 125 wall 15 and the adjacent surfaces 16 of the

- wall of the opening and a portion adapted to engage the inclined positioning wall of the opening when the wire fails to be held raised by a warp thread, whereby the inclined positioning wall of the opening cooperates with the guide to hold the bearing wall of the opening in firm engagement with a face of the guide, and a feeler which acts upon a dropped wire opposite the bearing wall.
- 5 2. In a warp stop motion for looms, the combination of drop wires provided with feeler arresting portions and each having an opening provided with a vertical bearing wall adjacent the feeler arresting portion and an opposite positioning wall inclined to and converging upwardly toward the vertical bearing wall, a drop wire guide extending through the opening of the drop wires and having a straight face adapted to engage 10 the bearing wall of the opening and back up the drop wire opposite and against the pressure of the feeler, and a portion adapted to engage the inclined positioning wall of the opening when a wire fails to be held raised by a warp thread, that the inclined positioning wall of the opening may cooperate with the guide to hold the vertical bearing wall of the opening in firm engagement with the straight face of the guide.
- 15 3. In a warp stop motion for looms, the combination of a feeler, a series of drop wires having laterally extending enlargements and provided with an elongated guide slot the wall of which at the side of the elongated slot adjacent to the enlargement is projected toward the opposite straight wall of the elongated slot, and a guide bar for engaging the projected wall of the slot for backing the 20 enlargement against the lateral pressure of the feeler and moving the drop wire laterally as it drops into the path of the feeler.
4. In a warp stop motion for looms, the combination of a feeler, a series of drop wires having narrow and wide portions and each provided with an elongated guide slot, one wall of which at the side of the elongated slot adjacent the wide portion of the drop wire is inclined and converges upwardly toward the opposite straight bearing wall, a guide bar for engaging the bearing wall of the slot when a drop wire is released by a warp thread to position the wide portion of the drop wire for contact by the feeler, said guide bar at such times backing the wide portion of the drop wire against the pressure of the feeler.
5. In a warp stop motion for looms, the combination of a feeler having a detecting movement above the plane of the warp threads, a series of drop wires having narrow and wide portions and each provided with an elongated guide slot, one wall of which at the side of the elongated slot adjacent the wide portion of the drop wire is inclined and converges upwardly toward the opposite straight bearing wall, a guide bar for engaging the bearing wall of the slot when a drop wire is released by a warp thread to position the wide portion of the drop wire for contact by the feeler, said guide bar at such times backing the wide portion of the drop wire against the pressure of the feeler.
